UNITED STATES PATENT OFFICE.

WHITCOMB L. JUDSON, OF CHICAGO, ILLINOIS.

CHAIN-MAKING MACHINE.

SPECIFICATION forming part of Letters Patent No. 699,760, dated May 13, 1902.

Application filed June 22, 1901. Serial No. 65,556. (No model.)

To all whom it may concern:

Be it known that I, WHITCOMB L. JUDSON, a citizen of the United States, residing at Chicago, in the county of Cook and State of Illinois, have invented certain new and useful Improvements in Chain-Making Machines; and I do hereby declare the following to be a full, clear, and exact description of the invention, such as will enable others skilled in the art to which it appertains to make and use the same.

My invention has for its especial object to provide an automatic machine for forming chains of the character described in my prior United States patents—to wit, No. 504,037, August 29, 1893, and No. 557,207, March 31, 1896, both entitled "Shoe-fastenings." In the commercial form of the fastenings disclosed in said patents the interlocking chains are made up of hooks and links. The links are formed from staples, the prongs of which are passed through eyes of the pairs of links and are then clenched to complete the links and connect the hooks. The machine in its most approved form is automatic in its action; but many of the features thereof may be used to great advantage in machines which are not automatic or which are partially automatic.

The automatic machine illustrated in the drawings and hereinafter specifically described may be briefly outlined as follows: The hooks are placed, by hand or otherwise, in magazines, by which they are held alined and properly spaced apart. A plurality of these hook-magazines are provided, and the loaded magazines are by a rotary gravity-actuated magazine-holder and coöperating guides successively moved into position to deliver the series of hooks held thereby to an intermittently-movable feed-screw which extends parallel to the delivered series of hooks. When one magazine is, under the action of the feed-screw, emptied of its hooks, it will under the overpoising weight of the several loaded magazines be thrown onward out of delivering position, and the next following loaded magazine will take its place in position to deliver its hooks to the feed-screw. Under the action of the feed-screw and coöperating guides the hooks are intermittently fed while held properly spaced to and past an

assembling-point, at which assembling-point the link-forming staples are applied. The link-forming staples are held in a stack by a supply-holder which delivers the same one at a time to the assembling-point with their prongs in line with eyes of the pair of hooks which at the time are positioned at the assembling-point. A reciprocating plunger coöperates with the delivery end of the staple-holder to feed the staples one at a time into the eyes of the positioned pair of hooks. While the inserted staple is held by the feeding-plunger the ends thereof are partially clenched by a pair of clenching-pincers, which are moved with a properly-timed action. At a later step in the feed movement of the chains the links are completed by a pair of coöperating reversely-movable clenching-dies, which complete the clenching of the ends of the applied staples. While the hooks are held stationary by the feed-screw a plurality of spacing-blades are moved between certain of the hooks which are in the vicinity of the assembling-point, to more accurately space and more firmly hold the hooks while the staples are being applied and their ends clenched to form the links. One of these so-called "spacing-blades" works directly in front of the pincers and assists in holding the applied staples while their ends are being bent by the pincers. Another of the blades works between the clenching-dies and serves also as a former or anvil to assist in giving the proper form to the finished link.

Under the action of the machine so far indicated a continuous chain would be formed. However, by means of a so-called "cut-out" device, which may be variably set, chain-sections of any desired length may be formed. This cut-out device operates at predetermined intervals to cause the staple-feeding plunger to skip a feed movement, and thereby to omit a staple from the chain.

With the foregoing outline in mind it will be easy to follow the detailed description which will now be given.

The machine is illustrated in the accompanying drawings, wherein like characters indicate like parts throughout the several views.

Figure 1 is a perspective view showing the complete machine as viewed from the rear side thereof. Fig. 2 is a perspective view

with some parts broken away and others removed, showing the principal mechanism of the machine viewed from the front thereof. Fig. 3 is a view, partly in horizontal section 5 and partly in plan and with some parts broken away and others removed, showing the bed-plate of the machine with certain of the parts mounted thereon. Fig. 4 is a transverse vertical section on the line $x^4 x^4$ of Fig. 3. Fig. 10 is a bottom plan view of the coöperating guide-cheeks removed from the bed-plate. Fig. 6 is an enlarged vertical section on the line $x^6 x^6$ of Fig. 3. Fig. 7 is a longitudinal section approximately on the line $x^7 x^7$ of Fig. 15, some parts being broken away. Fig. 8 is a perspective view of one of the hook-magazines. Fig. 9 is an end elevation of one of the hook-magazines. Fig. 10 is a transverse section in the plane indicated by the lines 20 $x^{10} x^{10}$ on Fig. 8. Fig. 11 is a detail in vertical section approximately in the plane indicated by the lines $x^{11} x^{11}$ of Fig. 2. Fig. 11^a is a skeleton view showing, on an alined scale, certain of the parts shown in Fig. 11. Fig. 12 is a detail in front elevation showing a portion 25 of the feed-screw and a blade-carrying head shown in Fig. 11. Fig. 13 is a section on the line $x^{13} x^{13}$ of Fig. 11. Fig. 14 is a vertical section on the line $x^{14} x^{14}$ of Fig. 11. Fig. 15 is a horizontal section taken approximately 30 on the line $x^{15} x^{15}$ of Fig. 2, some parts being removed and others being broken away. Fig. 16 is a vertical section approximately on the line $x^{16} x^{16}$ of Fig. 15. Fig. 17 is a detail in face 35 view of a clutch-ring removed from working position. Figs. 18, 19, and 20 are skeleton views in section approximately in the planes indicated, respectively, by the lines marked $x^{18} x^{18}$, $x^{19} x^{19}$, and $x^{20} x^{20}$ on Fig. 2. Figs. 21 40 and 22 are skeleton views in plan illustrating the actions of the chain, the staple-feeding plunger, the clenching-pincers, and the clenching-dies. Figs. 21^a and 22^a are fragmentary views, on an enlarged scale, showing 45 portions of the chain and portions of the devices for action thereon, which views correspond in the position of their parts, respectively, to Figs. 21 and 22. Fig. 23 is a detail view in front elevation, showing portions of 50 the so-called "cut-out" device. Fig. 24 is a section on the line $x^{24} x^{24}$ of Fig. 23, some parts being broken away. Fig. 25 is a section on the line $x^{25} x^{25}$ of Fig. 24. Fig. 26 is an enlarged view of the delivery end of the staple- 55 supply holder. Fig. 27 is a side elevation of the upper end of the staple-supply holder and the lower end of a coöperating detachable supplemental section thereof. Figs. 28 and 29 are horizontal sections, respectively, on 60 the lines x^{28} and x^{29} of Fig. 27. Figs. 30 and 31 are views, respectively in side elevation and plan, showing a section of the chain which is the product of the machine. Figs. 32 and 33 are detail views in plan showing, respectively, one of the hooks and one of the link-forming staples of the chain.

"Right" and "left" as used in this description are taken with respect to Fig. 2 and with the observer assumed to be standing facing the exposed front of the machine.

The characters $a a'$ indicate a suitable bed-plate which is supported at the proper altitude by a flanged pedestal a^2 , bolted to the floor. A long channel or screw-seat a^3 extends longitudinally from end to end of the 70 bed-plate $a a'$. Secured to the bed-plate at the ends of the screw-seat a^3 are suitable bearing-boxes a^4 .

Rigidly secured on the top of the bed-plate section a are heavy bearing-brackets a^5 , a^5 , a^6 , 80 and a^7 , all of which are removed in Fig. 3, but which are shown in Figs. 1, 2, 11, 15, 16, and 24. Secured on the bed-plate section a' near its extremities is a pair of bearing-plates a^8 , having bearing-hubs a^9 . (Best shown in 85 Figs. 1 and 3.)

The main driving-shaft b is loosely mounted in the pair of bearing-brackets a^5 (see Figs. 1, 2, 15, and 16) and is provided with a series of cams 1, 2, 3, 4, and 5, the functions and 90 construction of which will be given in connection with the descriptions of the various mechanisms which they operate. As shown, the shaft b is also provided with a hand-wheel b' , which enables it to be moved by hand- 95 power when desired.

In the operation of the machine the shaft b receives a continuous motion from a constantly-running driving-pulley b^2 , which is loosely mounted on the projecting right-hand 100 end of said shaft, as best shown in Figs. 2 and 15. The pulley b^2 is provided with a notched clutch-ring b^3 , fixed thereon. (See Figs. 15 and 17.) A spring-pressed clutch-dog b^4 , pivoted to a heavy collar b^5 , secured 105 on the shaft b adjacent to the clutch-ring b^3 , coöperates with the notches of said ring to connect said shaft for rotation with said driving-pulley. The dog b^4 is released from the ring b^3 by a shipper-collar b^6 , which slides on 110 the shaft b and is subject to the upper arm b^7 of a vertical rock-shaft b^8 , mounted in suitable bearings b^{10} , with its lower arm b^{11} pivoted to a long link b^{12} . As best shown in 115 Figs. 2 and 16, the left-hand end of the link b^{12} , as shown in Fig. 2, projects through a suitable passage in the pedestal a^2 and is connected to one arm of a bell-crank b^{13} , suitably pivoted to the said pedestal. The intermediate portion of the link b^{12} is connected to one 120 end of a spring b^{14} , the other end of which, as shown in Fig. 2, is attached to a pin b^{15} , depending from the bed-plate. The strength of this spring b^{14} is such that normally the spring-pressed clutch-dog b^4 will be held out 125 of engagement with the clutch-ring b^3 , and the driving-shaft b will stand idle. By stepping onto a footpiece b^{16} , pivoted to the pedestal a^2 and connected to the bell-crank b^{13} by the rod b^{17} , the clutch-dog b^4 is rendered 130 operative. The driving-shaft b will be driven as long as the footpiece is held down. Of

course a suitable lock might be provided for holding the said clutch-dog in driving position.

By reference to Fig. 32 it will be seen that 5 the hooks y have link-eyes y' , lacing-lugs y^2 , and side lugs y^3 .

The feed-screw c is mounted near its ends in the bearing-boxes a^4 and loosely fits the seat a^3 , with its upper surface exposed for action 10 on the hooks. The spiral groove in the screw c is of such cross-section as to closely fit the lacing-lugs y^2 of the hooks y . The tread or pitch of said screw c is such that the hooks will be held spaced longitudinally thereof the 15 proper distance to receive the ends of the staples z through their link-eyes y' . Near its right-hand end the threads of the screw c are cut away, as shown at c' , so that the finished chain will be dropped through the seat a^3 , 20 which at this point is cut through the bed-plate.

An intermittent rotary movement sufficient to move the pairs of hooks in succession to the assembling-point is given to the screw c' , 25 preferably by an intermittent-motion device known to the craft as the "Geneva" movement and illustrated in Fig. 16. As this movement is well-known, the following brief description thereof is sufficient: An arm d is 30 fast to the driving-shaft b and is provided with a laterally-projecting roller d' , which is adapted to engage intermittently with the radial grooves d^2 of a star-wheel d^3 , (shown as suitably mounted on a stud d^4) projected from 35 the right-hand bearing-bracket a^5 . Between the radial slots d^2 the star-wheel d^3 is provided with segmental notches d^5 , which fit the periphery of a lock-disk d^6 , carried by the driving-shaft b and itself provided with segmental notch d^7 , which permits the movement of 40 the star-wheel when and only when it is being acted upon by the roller d' . The star-wheel d^3 is secured to rotate with the spur-gear d^8 , which meshes with the spur-pinion d^9 , secured on the right-hand end of the feed-screw c . With this device the feed-screw is 45 moved during a one-quarter rotation of the driving-shaft b and is locked against movement throughout the other three-quarter rotation of said shaft.

The hook-magazines (best shown in Figs. 6 to 10, inclusive) are each made up of a pair of angle-irons f , having parallel closely-spaced flanges, which are rigidly secured by small shouldered bolts f' . Between the parallel flanges of said angle-irons f is a thin hook-spacing blade f^2 , which is provided at its outer edge with a series of hook seats or notches f^3 , as best shown in Fig. 7. The hook-seats f^3 are of the proper form to receive the hooked ends of the hooks y , and they are so spaced that they will hold the hooks properly spaced for delivery to the feed-screw c . The blade f^2 has slots f^4 , as shown in Fig. 1, through 60 which the shouldered portions of the bolts f' work to restrain said blade for movement transversely of the magazine. The blade f^2

is held by friction between the angle-bars f , and at its ends it is provided with cam-shoulders f^5 for a purpose which will hereinafter 70 appear. In Fig. 7 the spacing-blade f^2 is shown as partially retracted.

The hook-magazines are loaded with the hooks, while the spacing-blades f^2 are forced outward to their limit. The hooks set in the 75 magazines with their hook ends inward. By reference to Figs. 6, 9, and 10 it will be noted that the holding-faces of the angle-irons f are rabbeted at f^6 to receive the side lugs y^3 of the hooks y . 80

The loaded magazines are placed on an inclined feed-deck g , which, as shown, is supported by arms g' from the bearing-plates a^8 . By the feed-deck g the loaded magazines are directed to a rotary magazine-holder 85 afforded by a pair of sprocket-like disks g^2 , secured on a shaft g^3 , loosely mounted in the hubs a^9 of the bearing-plates a^8 . These disks g^2 are provided with notches g^4 , which afford clearance for the spacing-blades f^2 , and they 90 are further provided with sprocket-teeth g^5 , adapted to engage notches f^7 , cut in the base webs or flanges of the magazine-bars f , which base-flanges, it will be noted, are curved to fit the peripheries of the said disks g^2 . By 95 the teeth or spacing lugs g^5 the magazines are properly held and aligned and are delivered against the inner cylindrical surface of a concave guide-block g^6 , which extends nearly the full length of the magazine and 100 is provided at its ends with segmental retaining-plates g^7 . The cylindrical inner surface of the guide-block g^6 is provided with a series of segmental guide channels or grooves g^8 of such number and spacing that they are 105 adapted to receive the lacing-lugs y^2 of the hooks y and properly guide the same to the grooves of the feed-screw c . The overhanging-weight of the several loaded magazines on one side of the rotary magazine-holder 110 serves to automatically move the same under the action of gravity. Immediately after the hooks of the magazines are delivered to the guide-channels g^8 cam-surfaces g^9 (see Figs. 6 and 7) on the upper extremities of the 115 retaining-plates g^7 act on the cam-shoulders f^4 at the end of the spacing-blades f^2 of the magazines and gradually force the blades away from the hooks, so that when the hooks are delivered to the feed-screw the said spacing-blades are withdrawn therefrom sufficiently to clear the hooks and permit the same to be fed longitudinally of the screws. 120

When the hooks have been moved downward to a point vertically above the axis of the feed-screw c , in which position the lacing-lugs y^2 thereof are brought into the grooves of said screw, the said lacing-lugs strike against the sharp and straight edge of a fixed stop guide-bar g^{10} , as best shown in 125 Figs. 3 and 6. The hooks are, under the action of the feed-screw, fed step by step until the last hook is fed forward out of the magazine, whereupon the emptied magazine, being 130

then free to pass clear of and over the stop-bar g^{10} , is, under the weight of the loaded magazines, thrown onward out of the way and the next succeeding loaded magazine takes its place and delivers its hooks to the feed-screw. As shown, the emptied magazines thrown from the magazine-holder are caught by an apron g^{11} , suitably secured to the bed-plate section a' .

10 The hooks which are fed out from the ends of the magazine by the feed-screw are fed between the sharp edges of a pair of guide-bars h , (see Figs. 1, 2, 3, and 11,) which closely fit the upper surface of said screw and cause 15 the hooks to continue their travel longitudinally of the screw. To hold the hooks down in proper engagement with the screw, a pair of retaining plates or bars h' are mounted directly on top of the guide-bars h , preferably 20 by means of slot and screw connections h^2 and h^3 , which permit the retaining-plates h' to be separated, so that when desired or necessary the hooks may be lifted from the screw. On their under inner edges the retaining- 25 plates h' are rabbeted at h^4 , as best shown in Fig. 4, so as to receive and overlie the side lugs y^3 of the hooks y , thereby to insure the hooks being held down. The retaining-plates h' are yieldingly drawn into their closed positions, as indicated in Figs. 3 and 4, by means 30 of a coiled spring h^5 , shown as applied to pins h^6 , that depend from said plates h' and work through suitable limiting-slots h^7 in the bed-plate. By means of a toggle-lever h^8 , 35 applied to studs h^9 on said plates h' and provided with a stop-finger h^{10} , said plates may be held separated against the tension of the springs h^5 when desired.

When the hooks are fed onward from the 40 guide-bars h and retaining-plates h' , they are passed between a pair of properly-spaced 45 guide-cheeks h^{11} and h^{12} , which are rigidly secured to the bed-plate section a and are rabbeted at their inner edges at h^{13} , so that they 50 overlie the said lugs y^3 of the hooks and continue to hold the hooks down. These guide-cheeks h^{11} h^{12} are best shown in Figs. 3 and 5. The guide-cheek h^{11} is provided with a vertical staple-passage h^{14} and with undercut transverse blade-passages h^{15} and h^{16} , while the 55 guide-cheek h^{12} is provided with a transverse undercut blade-passage h^{17} , as best shown in Figs. 3, 5, and 11.

The staple-supply holder (best shown in 60 Figs. 2, 11, 11^a, 26, 27, 28, and 29) is afforded by a bar k , suitably secured in vertical position on the face of the supporting-bracket a' , as shown, by means of a clamp a^{10} . (See Figs. 1 and 13.) The bar k is provided with a staple-receiving rib k' , which in cross-section flares slightly outward, as shown in Fig. 29, so as to hold the staples z , the prongs of which, it will be noted, converge slightly.

The lower end of the supply-holder k terminates in position to deliver the staples directly into the staple-passage h^{14} of the guide-cheek h^{11} and to permit but one staple to be

fed under the same at one time. (See Figs. 11 and 11^a.) As illustrated in Figs. 27, 28, and 29, holder k is provided at its upper end 70 with the socket-section k^2 , which is adapted to receive the grooved end k^3 of a supplemental supply-holder or charging-stick k^4 .

In Fig. 26 k^5 indicates a removable pin for temporarily holding up the stack of staples z . 75

Mounted for reciprocating movements in a suitable seat extending transversely in the bed-plate section a in front of the feed-screw c is a divided or two-part slide 6 7, (shown best in Figs. 2, 3, 14, 12, and 22,) the sections 80 of which are normally locked together by a spring-pressed lock-bolt 8, shown as mounted in the section 7 and engaging a notch in the section 6. The left-hand end of the lock-bolt 8 is at a certain time and in a manner herein-after to be noted adapted to be forced into the notch 9 of the lock-block 10, secured on the bed-plate. The slide-section 6 receives positive motion from the cam 2 (see Figs. 2 and 18) through a bell-crank 11, pivoted on a 85 shaft 12, supported by the bearing-brackets a^5 . The lower arm of the bell-crank 11 is shown as connected to driving-lugs 13 on said slide-section 6, and the other arm of the said bell-crank is provided with a roller 14, which 90 works in a cam-groove 2^a of said cam 2. Working in a suitable seat extending transversely of the bed-plate section a at the rear side of the screw c is another slide 15, which, as shown, 95 is provided with driving-lugs 16. The slide 15 receives positive motion from the cam 3 (see Fig. 19) through a bell-crank 17, pivoted on a shaft 18, supported by the bearing-brackets a^5 . The lower arm of the bell-crank 17 is connected to the lugs 16 of said slide 15, while 100 the upper arm thereof is provided with a roller 19, which works in the cam-groove 3^a of the cam 3.

A pincer-operating cam-plate 20, having diverging cam-grooves 21 and driving-lugs 22, 110 is rigidly secured to a supplemental slide 23, mounted in a suitable seat in the slide 15, as best shown in Figs. 11, 14, 21, and 22. The cam-plate 20 receives positive motion from the cam 5 (see Fig. 20) through a bell-crank 115 24, mounted on the shaft 18, previously noted. The lower arm of this bell-crank connects to the lugs 22 of the cam-plate 20, and the upper arm thereof is provided with a roller 25, which works in a cam-groove 5^a of the cam 5. 120

The staple-feeding plunger m is rigidly and, as shown, adjustably secured on the section 7 of the front slide, and the projecting operative end m' thereof is flattened or reduced to blade-like form, to thereby adapt it for co-operation with the lower end of the staple-supply holder to feed one staple at a time, as indicated in Fig. 11^a.

The clenching-pincers n are pivoted to the rear slide 15 at n' , and they are also provided 130 with thin pinching-blades n^2 . The rear end of the pincer-levers are provided with rollers n^3 , which work one in each of the diverging cam-slots 21 of the cam-plate 20. The pincers

are closed by the inward movement of the cam-plate 20 with respect to the slide 15.

The coöperating clenching-dies *p* are mounted one on the rear slide 15 and the other 5 on the section 6 of the front slide. The projecting operating ends *p'* of these dies are also reduced to thin blades.

It may be here stated that the blade *m'* of the feed-plunger *m* works through the passage *h*¹⁵ of the guide-cheek *h*¹¹, that the blade *p'* of the front die *p* works through the passage *h*¹⁶ of said cheek *h*¹¹, and that the blade *n'* of the pincers *n* and the blade *p'* of the rear die *p* work through the passage *h*¹⁷ of the 15 guide-cheek *h*¹². The overlying portions of the guide-cheeks *h*¹¹ *h*¹² assist in holding the staples while they are being clenched to form the links. Attention is also called to the fact that the edges of the die-blades *p'* are cut to 20 the form which it is desired to give to the outer sides of the completed links, as best shown in Fig. 21a.

Under the action of the cams so far described the operations of the feed-plunger, 25 clenching-pincers, and the clenching-dies will be substantially as follows: In what we will assume for illustration to be the normal positions the parts stand as best indicated in Figs. 11, 11a, 18, 19, 20, 21, and 21a. The 30 plunger-blade *m'* at this time holds up the column of staples *z*, as best indicated in Fig. 11a; but the first action of the cam 2 is to move the slide 6, 7, and with it the staple-feeding plunger, outward far enough to allow the 35 column of staples to lower and the bottom member to fall upon the bed-plate. The next action of the cam 2 is to throw the said feed-plunger and also the front clenching-die *p* inward into the position indicated in Figs. 22 40 and 22a, under which movement said feed-plunger forces a staple through the eyes *y* of a pair of hooks positioned at the assembling-point. While the positioned staple is held by the feed-plunger *m* the slide 15 and cam- 45 plate 20 are given common movements under the actions of the cams 3 and 5, and the open pincers and the rear clenching-die *p* are moved into the positions indicated in Figs. 22 and 22a, in which position the open jaws 50 of the pincers are so located as to engage the ends of the inserted staple. Under the immediately-continued movement of the cams 3 and 5 the slide 15 is held stationary while the cam-plate 20 is forced inward, thereby 55 closing the pincers onto the ends of the inserted staple and partially clenching the same. The inward movements of the slide-section 6 and the slide 15, as above described, also forced together the clenching-dies *p* 60 against a partially-clenched link previously acted upon by the pincers, under an earlier feed movement of the screw, thereby coupling the link.

As shown in Figs. 11, 12, and 13, three spacing-blades *r* *r'* *r*² are carried by a vertically-movable head *r*³, which is in turn carried by

a slide *r*⁴, mounted to move vertically in the bearing-bracket *a*⁶. The slide *r*⁴ is provided at its upper extremity with a roller *r*⁵, which works in a cam-groove *4*^a of the cam 4. Under the action of the cam 4 the spacing-blades *r* *r'* *r*² are moved downward and held in their operative positions (indicated in Fig. 12) during all the time the feed-plunger *m*, pincers *n*, and dies *p* are performing their various 70 actions on the staples. The blade *r'* works between the pair of hooks at the assembling-point. The blade *r*² is passed through the partially-formed link which is located between the clenching-dies *p*, and the intermediate die *r* is passed through the intermediate partially-clenched staple and simply assists in holding the engaged hooks in position. 75

The so-called "cut-out" device in its most approved form is best illustrated in Figs. 2, 85 21, 22, 23, 24, and 25.

The cam *l* actuates the cut-out device, and it is provided with a peripheral channel or cam-groove *l*^a, which has a single jog or lateral bulge, shown both in Figs. 2 and 23. 90 A sleeve *t* is loosely journaled in the bearing *a*⁷ and has fixed to its rear end an arm *t'*, provided with a roller *t*², which works in the groove *l*^a of the cam *l*. A vibrating arm *t*³ is keyed to the forward end of said sleeve *t*, and 95 to the free upper end of this arm is pivoted a reversible double-ended driving-pawl *t*⁴, which is provided with a depending reversing finger or projection *t*⁵. The driving-pawl *t*⁴ is further provided with a depending V-shaped 100 retaining-lug *t*⁶, which coöperates with the reversely-beveled head of a spring-pressed plunger *t*⁷, mounted in the arm *t*³, to yieldingly hold the said pawl *t*⁴ operative in either position in which it may be set. 105

A short shaft *t*⁸ is loosely mounted in the sleeve *t* and projects at both ends. At its rear end said shaft *t*⁸ is shown as provided with a friction-disk *t*⁹, which is subject to an adjustable friction-clamp *t*¹⁰, anchored at *t*¹¹ 110 to the bearing *a*⁷. At its forward end said shaft *t*⁸ is keyed to a reversible ratchet-toothed disk *t*¹², the teeth of which are adapted for coöperation with the reversible driving-pawl *t*⁴. In its outer face the disk *t*¹² is provided with 115 a retaining-channel *t*¹³, to which, as shown, a pair of reversing-stops *t*¹⁴ are adjustably secured. The disk *t*¹² also carries a trip pin or projection *t*¹⁵. The reversing-stops *t*¹⁴ engage in succession with the trip-finger *t*⁵ of 120 the driving-pawl *t*⁴ to move and reverse the action of said pawl. 125

Mounted in a bearing *a*¹¹, secured on the bed-plate and in axial line with the notch 9 of the fixed lock-block 10, is a lock-tripping plunger *t*¹⁶, which is yieldingly drawn toward the right by a coil-spring *t*¹⁷, connected thereto and to said bearing-box *a*¹¹. The right-hand end of the trip-bolt *t*¹⁶ stands in position to be engaged by the trip-pin *t*¹⁵ of the 130 reversible ratchet-disk *t*¹², and the left-hand end of said bolt stands in position to engage

the head of the lock-bolt 8 and force the reduced left-hand end into the notch 9 of the fixed lock-block 10.

For each rotation of the driving-shaft *b* and 5 the cam *l*, and hence for each feed movement of the feed-screw *c*, the vibrating driving-pawl *t*⁴ is given sufficient movement to impart one tooth of movement to the ratchet-disk *t*¹². With the said pawls set as shown in Fig. 23 10 said disk will be moved in the direction indicated by the arrow marked thereon until the right-hand reversing-stop *t*¹⁴, by engagement with the reversing-finger *t*⁵ of the pawl *t*⁴, reverses the action of said pawl. When said 15 pawl *t*⁴ is reversed, said disk *t*¹² will be moved in a reverse direction until the left-hand stop *t*¹⁴ engages the said trip-finger *t*⁵ and throws the pawl *t*⁴ back into the position indicated in Fig. 23. The parts are so timed that the 20 trip-pin *t*¹⁵ of said disk *t*¹² will engage the trip-plunger *t*¹⁶ and force the same against the lock 8, while the slide 6-7 is moved to its extreme outer position, and while the plunger *t*¹⁶, lock 8, and notch 9 are alined and the 25 blade *m*' of the feed-plunger *m* is withdrawn from under the stack of staples. When the lock 8 is moved out of engagement with the notch in the slide-section 6 and into engagement with the notch 9 of the lock-block 10, 30 the said slide-section 6 is left free to impart the required movement to the front clenching-die *p*, while, on the other hand, the slide-section 7, with its staple-feeding plunger *m*, is locked stationary, so that a staple will be 35 omitted from the chain and the chain-section.

With the above-described device it is evident that the chain-sections will have twice as many links as there are notches included between the reversing-stops *t*¹⁴ of the disk *t*¹².

40 To illustrate, if the reversing-stops *t*¹⁴ are set fifteen notches apart the chain-sections will be separated by omitting a staple once in every thirty feed movements. The reversing-stops *t*¹⁴ may be set to give chain-sections of 45 any desired length.

The following table gives, briefly, the relative timing of the various parts, which are operated from the driving-shaft 3 and cams carried thereby, figured in degrees of movement of said driving-shaft. First, ninety degrees imparts complete feed movement to feed screw *c*. Between fifty and ninety degrees, front slide 6-7, with staple-feed plunger *m* and front clenching-die *p*, is moved outward to limit. Between eighty and one hundred and thirty-five degrees, spacing-plungers *r* *r'* *r*² are moved downward to operative positions, and are held down between one hundred and thirty-five and two hundred and 55 seventy degrees. Between one hundred and thirty-five and one hundred and eighty degrees, front slide 6-7 with staple-feed plunger *m* and front clenching-die *p* are moved inward to limit. Between one hundred and 60 eighty and two hundred and twenty-five degrees, rear slide 15 and cam-plate 20, with clenching-pincers *n* and rear clenching-die

70 *p* are moved inward to limit. Between two hundred and twenty-five and two hundred and sixty degrees, jaws of pincers are closed. Between two hundred and seventy and three hundred and thirty degrees, staple-feed plunger *m*, clenching-die *p* move outward or back to their normal position. Between ninety and one hundred and thirty-five degrees, driving-pawl *t*⁴ of the cut-out device receives its vibratory movement.

75 From the introductory outline and the foregoing detailed description it is thought that the construction and operation of the machine as an entirety must be distinct.

80 By actual usage the efficiency of the machine herein disclosed has been fully demonstrated.

85 It will be further understood that the machine is capable of general use wherever chains are to be formed from block-links and link-forming staples or similar chain-forming elements.

90 What I claim, and desire to secure by Letters Patent of the United States, is as follows:

1. In a machine adapted to form a chain from hooks and link-forming elements, the combination with means for holding the hooks longitudinally spaced, of means for applying the link-forming elements to the pair of positioned hooks while longitudinally spaced.

2. In a machine adapted to form a chain from hooks and link-forming elements, the combination with means for holding the hooks longitudinally spaced, of means for feeding the prongs of the staples into eyes of the pair of positioned hooks, while longitudinally spaced, and means for clenching the ends of the said staples to complete the links.

105 3. In a machine adapted to form a chain from hooks and link-forming elements, the combination with means for intermittently feeding the hooks and holding the same properly spaced, of means for intermittently feeding the staples into eyes of the pair of positioned and longitudinally-spaced hooks, and means for clenching the ends of the inserted staples to complete the links.

110 4. In a machine adapted to form a chain from hooks and link-forming staples, the combination with means for feeding the hooks and holding the same longitudinally spaced, of a supply-holder for the staples, a staple-feeding device coöperating with the delivery end of said holder to feed the staples, one at a time, into eyes of the pair of positioned and longitudinally-spaced hooks, and means for clenching the ends of the inserted staples to complete the links.

115 5. In a machine adapted to form a chain from hooks and link-forming staples, the combination with means for intermittently feeding the hooks and holding the same longitudinally spaced, of a supply-holder for the staples, a reciprocating feed-plunger coöperating with the delivery end of the said holder to feed the staples, one at a time, into eyes of the pair of positioned and longitudinally-

spaced hooks, and means for clenching the ends of the inserted staples to complete the links.

6. In a machine adapted to form a chain from hooks and link-forming staples, the combination with means for feeding the hooks and holding the same longitudinally spaced, of means for feeding the staples into eyes of the pair of positioned and longitudinally-spaced hooks, a pair of clenching-pincers for partly clenching the ends of the inserted staples and a pair of coöperating clenching-dies for completing the links.

7. In a machine adapted to form a chain from hooks and link-forming staples, the combination with means for intermittently feeding the hooks and holding the same properly spaced, of a supply-holder for the staples, a reciprocating feed-plunger coöperating with the delivery end of the said holder to feed the staples, one at a time, into eyes of a pair of positioned hooks, a pair of clenching-pincers for partially clenching the ends of the inserted staples, and a pair of coöperating clenching-dies for completing the links.

8. In a machine adapted to form a chain from hooks and link-forming staples, the combination with means for intermittently feeding the hooks and holding the same properly spaced, of a supply-holder for the staples, a pair of reversely-reciprocating slides, a feed-plunger on one of said slides, coöperating with the delivery end of said staple-holder to feed the staples, one at a time, into eyes of a pair of positioned hooks, a pair of pincers carried by the other slide and operating to partially clench the ends of the inserted staples, and a pair of coöperating clenching-dies carried, one by each slide, and operating to complete the links.

9. In a machine adapted to form a chain from hooks and link-forming staples, the combination with means for intermittently feeding the hooks and holding the same properly spaced, of a supply-holder for the link-forming staples, a pair of reversely-reciprocating slides, a feed-plunger on one of said slides coöperating with the delivery end of said holder to feed the staples, one at a time, into eyes of a pair of positioned hooks, a pair of pincers pivoted to one of said slides and operating to partially clench the ends of the inserted staples, a pincer-operating cam-plate movable first with and then with respect to the pincer-carrying slide, a pair of clenching-dies carried one by each slide and operating to complete the links, and automatic means for moving the said parts with properly-timed actions.

60 10. In a machine adapted to form a chain from hooks and link-forming staples, the combination with a feed-screw for feeding and holding the hooks longitudinally spaced, of means for applying the link-forming elements to the pair of positioned and longitudinally-spaced hooks.

11. In a machine adapted to form a chain

from hooks and link-forming elements, the combination with a feed-screw for feeding and holding the hooks longitudinally spaced, of 70 means for holding the said hooks subject to said screw, and causing the same to move in a series extending in longitudinal line, parallel to said screw, and means for applying the link-forming elements to the pair of positioned and longitudinally-spaced hooks. 75

12. In a machine adapted to form a chain from hooks and link-forming staples, the combination with an intermittently-movable feed-screw, for feeding and holding the hooks in a 80 longitudinally-spaced series, of means for feeding the prongs of the link-forming staples into eyes of the pair of positioned and longitudinally-spaced hooks, and means for clenching the ends of the inserted staples to complete the links. 85

13. In a machine adapted to form a chain from hooks and link-forming staples, the combination with an intermittently-movable feed-screw and coöperating guide-channel for guiding and feeding the hooks in a longitudinally-spaced series, of a staple-supply holder, a reciprocating feed-plunger coöperating with the delivery end of said holder to feed the staples, one at a time, into eyes of a pair of 95 positioned hooks, and means for clenching the ends of the inserted staples to complete the links. 90

14. In a machine adapted to form a chain from hooks and link-forming elements, the combination with a feeding device serving to hold the hooks properly spaced, of a plurality of magazines for the hooks, a rotary magazine-holder, and guide operating to deliver said magazines to said holder, at one side 105 thereof, which holder is operated by the over-poising-weight of said magazines and automatically delivers the hooks to said feed device.

15. In a machine adapted to form a chain 110 from hooks and link-forming elements, the combination with a hook-feed device serving to hold the hooks properly spaced, of a magazine for the hooks, means for moving said magazine into a position to deliver said hooks 115 to said feed device, and means for applying the link-forming elements to the hooks.

16. In a machine adapted to form a chain from hooks and link-forming elements, the combination with a hook-feeding device serving 120 to hold the hooks properly spaced, of a magazine for holding and spacing the hooks in an alined series, a rotary magazine-holder operating to move said magazine transversely of the line of feed, into a position to deliver 125 said hooks to said feeding device, and means for applying the link-forming elements to said hooks while the hooks are subject to said feeding device.

17. In a machine adapted to form a chain 130 from hooks and link-forming elements, the combination with a hook-feeding device serving to hold the hooks properly spaced, of a magazine for holding and spacing the hooks

in an alined series, a stop-bar extending longitudinally of said feed device, a rotary magazine-holder operating to move said magazine transversely of the line of feed and to deliver 5 the hooks to said feed device and against said stop-bar, and means for applying the link-forming elements to the hooks while they are subject to said feed device.

18. In a machine adapted to form a chain 10 from hooks and link-forming elements, the combination with a feeding device serving to hold the hooks properly spaced, of a magazine for holding and spacing the hooks in an alined series, a stop-bar extending in the line of feed, 15 a rotary magazine-holder operating to move said magazine transversely of the line-feed and deliver the hooks to the said feed device and against said stop-bar, a grooved concave guide coöperating with said holder to deliver 20 said hooks to said feed device, and means for applying the link-forming elements to the hooks while they are subject to said feed device.

19. In a machine adapted to form a chain 25 from hooks and link-forming elements, the combination with an intermittently-movable feed-screw, of a magazine for holding and spacing the hooks in an alined series, means for moving said magazine transversely of the line 30 of feed, and into position to deliver the hooks, properly spaced, to said feed-screw, and means for applying the link-forming elements to the hooks while they are subject to said feed-screw.

35 20. In a machine adapted to form a chain from hooks and link-forming elements, the combination with an intermittently-movable feed-screw, of a magazine for holding and spacing the hooks in an alined series, a stop- 40 bar extending in the line of feed and into a position to deliver said hooks, properly spaced, to said feed-screw and against said stop-bar, and means for applying the link-forming elements to the hooks while they are subject to 45 said feed-screw.

21. In a machine adapted to form a chain from hooks and link-forming elements, the combination with a hook-feeding device serving to hold the same properly spaced, of a 50 magazine for holding and spacing the hooks in an alined series, a gravity-actuated holder for said magazine operating to move the same transversely of the line of feed and to deliver the said hooks, properly spaced, to said feed- 55 ing device and means for applying the link-forming elements to the said hooks while they are subject to said feeding device.

22. In a machine adapted to form a chain 60 from hooks and link-forming elements, the combination with a feed-screw serving to hold the hooks properly spaced, of a stop-bar extending longitudinally of said feed-screw, a magazine for holding and spacing the hooks in an alined series, a gravity-actuated rotary 65 magazine-holder operating to move said magazine laterally and to deliver the hooks to said feed-screw, properly spaced, and against said

stop-bar, and with the magazine clear of said stop - bar, whereby a continuous supply of loaded magazines is afforded.

23. In a machine adapted to form a chain 7c from hooks and link-forming staples, the combination with means for holding the hooks in a longitudinally-spaced series, of means for feeding the staples into the eyes of adjacent 75 longitudinally-spaced hooks and clenching the ends of the same, one or more spacing-blades, and means for intermittently moving said spacing-blades between the assembled hooks, for coöperation with the clenching means.

24. In a machine adapted to form a chain 80 from hooks and link-forming staples, the combination with means for holding the hooks spaced, of means for feeding the staples into eyes of the positioned hooks and clenching 85 the ends of the same, and one or more blades movable between the assembled hooks for securely holding and insuring the accurate spacing of the hooks.

25. In a machine adapted to form a chain 90 from hooks and link-forming staples, the combination with means for intermittently feeding the staples into eyes of the positioned hooks, means for clenching the ends of the inserted staples, and a plurality of spacing- 95 blades intermittently movable between the assembled hooks, for insuring accurate spacing of the hooks, and at least one, thereof, serving as a former or anvil for coöperating with the clenching means.

26. In a machine adapted to form a chain 100 from hooks and link-forming staples, the combination with means for intermittently feeding the hooks and holding the same properly spaced, of means for feeding the staples into 105 eyes of the positioned hooks, a pair of clenching-pincers for partially clenching the ends of the inserted staples, a pair of coöperating clenching - dies for completing the links, a spacing-blade insertible between the hooks 110 in front of said pincers, and a forming-blade insertible between the hooks, at a point between said clenching-dies.

27. In a machine adapted to form a chain 115 from hooks and link-forming elements, the combination with means for feeding and holding the hooks in a longitudinally-spaced series, of means for intermittently applying the link-forming elements to the pair of positioned and longitudinally - spaced hooks, and a cut-out device operating at predetermined intervals to cause a link-forming element to be omitted and the chain to be sectioned.

28. In a machine adapted to form a chain 125 from hooks and link-forming elements, under a continuous action, the combination with a cut-out device operating, at predetermined intervals to cause a chain element to be omitted, which cut-out device involves a reversible, toothed ratchet member having a pair of reversing-stops, of a vibrating reversible driving-pawl coöperating with the teeth of 130 said toothed ratchet member, and itself

adapted to be reversed by the said reversing-stop thereof.

29. In a machine adapted to form a chain from hooks and link-forming staples, the combination with means for intermittently feeding the hooks and holding the same in a longitudinally-spaced series, of a supply-holder for the staples, a reciprocating feed-plunger coöperating with the delivery end of said holder to feed the staples, one at a time, into eyes of the pair of positioned and longitudinally-spaced hooks, and a cut-out device operating at predetermined intervals to intercept the feed movement of said plunger and cause a staple to be omitted, thereby determining the length of the chain-sections.

30. In a machine adapted to form a chain from hooks and link-forming staples, the combination with means for feeding the hooks and holding the same properly spaced, of a supply-holder for the staples, a staple-feeding device operating to intermittently feed the staples from said holder and apply the same to the hooks, and a cut-out device comprising a reversible ratchet member having a pair of spaced reversing-stops, a vibrating reversible driving-pawl coöperating with the teeth of said toothed member and itself reversed by the reversing-stops thereof, and a trip actuated by said reversible toothed member for causing said staple-feeding device to skip feed movements at predetermined intervals.

31. In a machine adapted to form a chain from hooks and link-forming staples, the combination with means for feeding and holding

the hooks properly spaced, of a supply-holder for the link-forming staples, a reciprocating feed-plunger coöperating with the delivery end of said holder, to feed the staples, one at a time, into eyes of a pair of positioned hooks, a reciprocating driver for said feed-plunger, a lock normally connecting said feed-plunger to its driver, and a cut-out device for tripping said lock out of action at predetermined intervals, comprising a ratchet-disk with a lock-tripping pin or part, a pair of reversing-stops on said disk, and a vibrating arm provided with a pivoted reversible pawl having a pawl-reversing finger which works between and is acted upon by said reversing-stops.

32. In a machine adapted to form a chain from hooks and link-forming elements, under a continuous action, of a cut-out device operating at predetermined intervals, to cause a chain element to be omitted, which cut-out device involves a reversible toothed ratchet member having a pair of reversing-stops, at least one of which stops is adjustable with respect to the other, to vary the length of the chain-sections, and a vibrating reversible driving-pawl coöperating with the teeth of said toothed member and itself adapted to be reversed by the said reversing-stop thereof.

In testimony whereof I affix my signature in presence of two witnesses.

WHITCOMB L. JUDSON.
